UNITED STATES PATENT OFFICE

161,094

RUBBER BOOT

James F. Eldon, Melrose, Mass., assignor to Converse Rubber Corporation, Malden, Mass., a corporation of Massachusetts

Application July 1, 1950, Serial No. 10,914

Term of patent 14 years

(Cl. D7—4)

To all whom it may concern:

Be it known that I, James F. Eldon, a citizen of the United States of America, residing at Melrose, in the county of Middlesex and Commonwealth of Massachusetts, have invented a new, original, and ornamental Design for a Rubber Boot, of which the following is a specification, reference being had to the accompanying drawing, forming part thereof.

Fig. 1 is a plan view of a rubber boot showing my new design;

Fig. 2 is in elevation of the left side of the rubber boot;

Fig. 3 is a plan view of the boot with the top cuff thereof folded downwardly; and

Fig. 4 is an elevation of the right side of the boot as shown in Fig. 3.

The irregular lines on the inside of the top cuff and the inside of the tongue of the boot indicate a lining of shearling or the like.

I claim:

The ornamental design for a rubber boot, substantially as shown and described.

JAMES F. ELDON.
